(57) **CLAIM**

The ornamental design for a telescopic rod, as shown and described.

DESCRIPTION

FIG. 1 is a front, right, and top perspective view of a first embodiment of a telescope rod showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of an area labeled 9 in FIG. 1.

FIG. 10 is a partial enlarged view of an area labeled 10 in FIG. 1.

FIG. 11 is another front, right and top perspective view of the telescopic rod in a usable state.

FIG. 12 is a front, right and top perspective view of a second embodiment of a telescopic rod.

FIG. 13 is a rear, left and bottom perspective view thereof.

FIG. 14 is a front elevation view thereof.

FIG. 15 is a rear elevation view thereof.

FIG. 16 is a left side elevation view thereof.

FIG. 17 is a right side elevation view thereof.

FIG. 18 is a top plan view thereof.

FIG. 19 is a bottom plan view thereof;

FIG. 20 is a partial enlarged view of an area labeled 20 in FIG. 12; and,

FIG. 21 is another front, right and top perspective view of the telescopic rod in a usable state.

The broken lines shown in the drawings are included for the purpose of illustrating portions of the telescopic rod that form no part of the claimed design. In addition, the dot-dash broken lines in FIGS. 1, 9, 10, 12 and 20 depict the boundaries of the enlargements that form no part of the claimed design.

1 Claim, 21 Drawing Sheets
